United States Patent Office

Des. 196,776
Patented Nov. 5, 1963

196,776

OVERSHOE

Emma Jane Klinker, 512 Arden Blvd., Los Angeles, Calif.

Filed June 27, 1963, Ser. No. 75,564

Term of patent 14 years

(Cl. D7—4)

The essential features of my design reside in the full line disclosure on the drawing.

I claim:

The ornamental design for an overshoe, substantially as shown and described.
